STEAM HEATER REGULATOR

Filed Feb. 7, 1931

FIG. 1

FIG. 2

Inventor

Louis C. Hyatt

By his Attorney

E. M. Bentley

UNITED STATES PATENT OFFICE

1,932,666

STEAM-HEATER REGULATOR

Louis C. Hyatt, Albany, N. Y., assignor to Consolidated Car-Heating Company, Inc., Albany, N. Y., a corporation of New York

Application February 7, 1931. Serial No. 514,238

5 Claims. (Cl. 137—71)

For a detailed description of the present form of my invention, reference may be had to the following specification and to the accompanying drawing, forming a part thereof, wherein

5 Fig. 1 shows a vertical cross section of my regulator and

Fig. 2 shows a plan of the same looking at it from the bottom as it appears in Fig. 1.

In the application of Lee P. Hynes, filed November 19, 1926, Serial No. 149,510 and the application by same applicant, filed January 24, 1930, Serial No. 433,222, there is shown a steam-heating means for busses wherein the automatic regulation is effected by an outside expansible chamber

15 remote from the boiler but connected with the sealed pipe system and acting, under the internal pressure, to suck into itself more or less of the water of the boiler system. Such abstraction

20 of water tends to reduce the heating effect of the boiler and, of course, to also reduce the pressure which has caused the water-withdrawing action of the chamber. In this manner the pressure and

activity of the boiler is maintained automatically at the desired degree. My present invention re-

25 lates to an improvement in the regulating chamber for the type of system just mentioned. It involves a separable enclosing case, to the base

portion of which the piping system is permanently connected while the other part is removable

30 from said base. Inside of this casing is a separate chamber which is bodily expansible and contractible so as to change its cubic volume, be-

coming larger as it expands and thereby sucks thereinto the water from the boiler. Moreover,

35 the contraction of the aforesaid chamber is produced positively by a spring, whereby the entire device may be placed either above or below the level of the boiler, because the chamber action is by virtue of the spring rendered independent

40 of gravity.

This regulator is a small affair, being in out-

side dimensions but six or seven inches in height and five inches in diameter. That is because only

45 about a pint of water is required in the sealed pipe-system for busses. It is to be understood, however, that the dimensions and capacity stated

are given solely for purposes of illustration, and without intent to limit the invention.

In the drawing, the figure is a sectional view

50 illustrating a regulator constructed in accordance with the invention.

Referring to the drawing, 3 represents a hollow

cylinder, preferably of cast aluminum open at its lower end. 2 is a flat circular base resting on

55 three screw-hole feet or projections at its periph-

ery. The cylinder 3 is seated on this base 2 and engages therewith by means of a bayonet joint, as appears in Fig. 2. In the center of the base is a screw-threaded hole entered by a hollow sealing screw 8 through which passes the pipe 7 leading from the heater pipe-system. Inside of cylinder 3 is a sealed bellows or corrugated vessel 6 seated at its bottom on the top face of aforesaid base 2 and communicating through screw 8 with the aforesaid pipe 7. The top face of bellows 6 is formed with a deep central depression, which contains the central spring-holding socket of a pressure-plate 4 that is seated on the bellows. Plate 4 also has a central depression extending down into the interior of the bellows, while, above said downward extension is the flat flange portion of the plate resting on the upper edge of the corrugated side wall of the bellows 6.

A heavy spring 5 is interposed between the said plate 4 and the top of the aforesaid cylinder 3 which cylinder has on its inside a receiving socket for the upper end of the spring corresponding to the socket or depression for its lower end formed in the downward extension of the said plate 4. In the collapsed condition shown in the

55 drawing, the interior of the bellows is substantially occupied by its depressed top plate enclosing the central spring-socket or depression on plate 4 which enters the depression in the top of the bellows. But when the pressure on the

60 pipe system forces the contents of that system up through pipe 7 into the bellows 6, the corrugated side walls of the bellows will expand upwardly against the downward pressure of spring 5 carrying up with it its depressed top plate. The

65 boiler water from the system will be drawn thereby out of the boiler and pipe system into the expanded bellows. Even if the contents of the pipe

70 system enter the bellows in the form of steam, that steam is speedily condensed into water inside of the bellows and the ultimate effect of

75 withdrawing water from the boiler and pipe system into the bellows is attained. By such withdrawal of water from the boiler the pressure

80 caused by heating of the boiler and tending to cause the withdrawal, is diminished until a balance between said pressure and the amount of water withdrawn is established at any desired

85 point. The spring 5 acts in opposition to the pressure in the system and tends to cause positively the collapse of the bellows and the positive

90 expulsion of the water therefrom. That occurs in whatever position the regulator may be located

95 with respect to the boiler which is of particular value in a bus-heater since it permits the placing

100

105

110

of the regulator at different points in the bus as may be required by the form and construction of the bus body. Obviously, too, the cubic capacity of the regulator is automatically increased 5 or diminished in proportion to the degree of control which it exerts on the system. That also is an aid in keeping down the size and cost of the apparatus, since the chamber 6 expands in proportion to the amount of water it has to accommodate.

10 What I claim as new and desire to secure by Letters Patent is:

1. An automatic regulator for a steam heating system comprising a base provided with a central opening, an expandible chamber attached to said base and provided with an expandible and contractible wall having a central depressed portion, an abutment plate separate from said chamber and having a central depressed portion complementary to the depressed portion of said chamber 15 and provided with a flange resting on the top of and supported by said chamber, a casing removably engaging said base, a spring having one end bearing against the depressed portion of the abutment plate and the other end bearing against 20 the top of said casing, and means for connecting the interior of said chamber with a source of fluctuating pressure through said opening.

2. An automatic regulator for a steam heating system comprising a sealed chamber having an expandible and contractible wall provided with a central longitudinally depressed portion, an abutment plate having a central longitudinally depressed portion complementary to and removably 35 projected into the depressed portion of said chamber, said abutment plate having a flange removably resting upon the top wall of said chamber, means for maintaining a yieldable collapsing pressure upon said abutment plate, and means for connecting the interior of the chamber with 40 a source of fluctuating pressure.

3. An automatic regulator for a steam heating system comprising a supporting base, an expand-

sible and contractible member connected with said base and cooperating therewith to provide a sealed expandible member, said member having a top wall provided with a central longitudinally depressed portion, said base having a single pressure opening communicating with the interior of said chamber, an abutment plate having a central depressed portion complementary to and fitting within the depressed portion of said chamber and provided with a flange removably resting upon the top of said chamber, and means for maintaining a yieldable pressure upon said abutment plate.

4. An automatic regulator for a steam heating system comprising a base, a sealed chamber attached to said base and provided with an expandible and contractible wall and with a top wall provided with a central longitudinally depressed portion, an abutment plate removably resting on and normally supported by the top wall of said chamber, a casing enclosing said chamber and detachably engaging said base, a spring interposed between said abutment plate and an end of said casing, said spring being constructed and arranged to maintain a yieldable collapsing pressure upon said abutment plate, and means for connecting said chamber with a source of fluctuating pressure.

5. An automatic regulator for a steam heating system comprising a base, a sealed chamber attached to said base and provided with an expandible and contractible wall, an abutment plate removably resting on and normally supported by the top wall of said chamber, a casing enclosing said chamber and detachably engaging said base, a spring interposed between said abutment plate and an end of said casing, said spring being axially positioned with respect to said casing and said chamber so as to apply a yieldable collapsing pressure at the center of the top wall of said chamber, and means for connecting said chamber with a source of fluctuating pressure.
